UNITED STATES PATENT OFFICE.

LUTHER A. HOLCOMBE, OF NASHVILLE, ARKANSAS.

PLOW.

1,032,546.

Specification of Letters Patent. Patented July 16, 1912.

Application filed May 16, 1911. Serial No. 627,485.

To all whom it may concern:

Be it known that I, LUTHER A. HOLCOMBE, a citizen of the United States, residing at Nashville, in the county of Howard and State of Arkansas, have invented 5 certain new and useful Improvements in Plows, of which the following is a specification.

This invention has relation to new and 10 useful improvements in plows and especially in plow stocks.

The main object of my invention is to provide an adjustable standard to accommodate any type of plow; to facilitate the 15 use of the plow in tight or loose ground and to adapt the plow to a high or low horse.

A further object of my invention is to provide an adjustable colter and clamping 20 means therefor which adapt the colter for adjustment.

With the foregoing and other objects in view my invention consists of the novel features of construction, combination and arrangement of parts as are described in this 25 specification, illustrated in the accompanying drawings forming a part thereof and particularly pointed out in the appended claim.

30 Reference being had to the drawings: Figure 1 is a side elevational view of my plow. Fig. 2 is a top plan view thereof. Fig. 3 is a perspective, detail view of the clamping blocks employed between the 35 beams of the plow, said blocks being part of the means by which the colter and standard can be adjusted. Fig. 4 is a perspective view of the colter. Fig. 5 is a perspective view of said standard.

40 Referring more particularly to the drawings, in which like numerals designate like parts throughout, my invention, in detail, is described as follows:

The plow comprises two beams 1 and 2 45 extending longitudinally. Between said beams is provided a pair of clamping blocks 3 and 4. Each of said blocks is provided upon its inner face with a recess 5, said recesses, in conjunction with each other forming a rectangular opening 6, from which the upper portion of the colter 7 extends. Said colter 7 may be adjusted vertically by releasing the tension thereon, which is accomplished by loosening the nut 7 provided 50 upon the end of the bolt 8, which bolt extends through the horizontal perforations 9

in said clamping blocks 3 and 4 and corresponding registering perforations in the longitudinal beams 1 and 2.

The plow foot 10 is pivotally interposed 60 between the rear ends of the beams 1 and 2 by means of a nut and bolt connection 11 extending through perforations 12 in the upper ends of the prongs 13 of said standard and corresponding registering perforations 65 in the rear ends of said beams. Extending through a perforation 14 provided in the clamping blocks 3 and 4 is a grass rod 15, which rod extends between the prongs 13 of the foot 10. A bolt 16 passes 70 through an eyelet provided at the lower end of the grass rod 15 and the corresponding perforations 17 which are provided in the walls of the prongs 13 of said standard. The bolt 16 passes through the eyelet provided 75 at the lower end of the grass rod in such manner that the grass rod is pivotally held in position to said foot, thereby enabling the standard to be adjusted by an adjustment of the grass rod within the 80 perforation 14. The grass rod 15 is adjusted in said perforation by an adjustment of the nuts 18 thereon, which nuts are engaged by threads 19 of the grass rod. Once the grass rod has been adjusted to the proper 85 point the nuts 18 are caused to tightly bind the abutments 20 of the clamping blocks, the faces of said abutments being in parallel relation to the faces of their respective nuts. Thus it will be seen that when the 90 nuts are binding against the faces of their respective abutments the grass rod 15 is held positively against movement thereby securing the standard 10 rigidly in position, and against movement. The plow is also 95 provided with handles 21 and braces 22 interposed between said handles and respective longitudinal beams, the lower ends of said braces being secured to the beams by means of said nut and bolt connection 11. 100

Having described my invention what I claim as new and desire to secure by Letters Patent, is:

In a plow of the kind described, the combination of two longitudinal beams, with 105 a pair of clamping blocks held therebetween, said clamping blocks each having a recess cut upon its inner face, said recesses in conjunction with each other forming a slanting perforation, a standard pivotally held to the rear end of the beams, said foot provided with prongs, a grass rod extend-

ing through the perforation in the clamping blocks, one end of said grass rod pivotally interposed between the prongs of the standard, said grass rod adapted to be adjusted within said perforation thereby altering the position of the standard when desired, and means comprising nuts to secure the grass rod against movement when

said rod has been adjusted to the proper point.

10

In testimony whereof I affix my signature in presence of two witnesses.

LUTHER A. HOLCOMBE.
